UNITED STATES PATENT OFFICE.

ARTHUR R. HAVENER, OF WAYLAND, MASSACHUSETTS, ASSIGNOR TO JUDSON L. THOMSON MFG. CO., A CORPORATION OF MASSACHUSETTS.

MACHINE FOR FEEDING CIRCULAR RIVET-CAPS AND THE LIKE.

1,342,331.

Specification of Letters Patent.

Patented June 1, 1920.

Application filed December 31, 1918. Serial No. 269,069.

To all whom it may concern:

Be it known that I, ARTHUR R. HAVENER, a citizen of the United States, residing at Wayland, in the county of Middlesex and 5 State of Massachusetts, have invented new and useful Improvements in Machines for Feeding Circular Rivet-Caps and the like, of which the following is a specification.

This invention relates to machines for 10 feeding and positioning disk shaped articles such as rivet caps and the like.

The object of the invention is to provide a simple and efficient means for feeding 15 rivet caps which shall effect the rolling of said caps upon their peripheries rather than the sliding of the caps upon their faces, especially along such portions of a raceway as may be slightly inclined to the horizontal, whereby the possibility of the clogging of 20 said raceway by failure of the caps to pass along the same is reduced to a minimum, and at the same time the speed at which the caps will move along said raceway is increased.

25 The invention consists, particularly, in the formation and arrangement of the different parts constituting the raceway by which the rivet caps are fed from a hopper to the rivet and cap setting instrumentalities.

30 The invention further consists in so combining the raceway with the reciprocatory feed slide that the rivet caps are changed in position from a vertical position in which 35 they roll upon their edges to a horizontal position in which they are fed by said slide.

The invention further consists in the combination and arrangement of parts set forth in the following specification and particularly pointed out in the claims thereof.

40 In the specification and drawings I have described and illustrated my invention as embodied in a machine of the type disclosed in U. S. Patent No. 1,276,652 issued to me

45 August 20, 1918.

Referring to the drawings:

Figure 1 is a left hand side elevation of a rivet and cap setting machine with features embodying this invention shown in 50 connection therewith, parts of said machine being broken away to save space in the drawing.

Fig. 2 is a vertical section taken in a

plane extending from the front to the rear of the machine through the center of the 55 setting instrumentalities.

Fig. 3 is a detail plan view of the lower portion of the cap feeding raceway.

Fig. 4 is a transverse section through said raceway taken on the line 4-4 of Fig. 3 60 illustrating the initial step in the operation of transferring a cap from the inclined section of the raceway to the horizontal section thereof.

Fig. 5 is a section similar to Fig. 4 illustrating the second step in said transferring operation.

Fig. 6 is a transverse section through the inclined raceway taken on line 6-6 of Fig. 1.

Fig. 7 is a detail horizontal section taken on line 7-7 of Fig. 5.

Like numerals refer to like parts throughout the several views of the drawings.

In the drawings, 1 is the frame of a rivet 75 and cap setting machine, and extending forwardly from the frame 1 is an arm 2 bearing at its outer end a work-support 3. An anvil 4 is arranged to reciprocate vertically in the outer portion of said arm in coöperation with a rivet driver 5 suitably arranged to be reciprocated in the frame 1 above said anvil by a pivoted lever 6 adapted to be operated by a crank 7 formed upon the driving shaft 8 of the machine, said crank 7 being connected with said lever by a link 9. The anvil 4 is reciprocated at the proper time in the operation of the machine by a lever 10 pivoted at 11 in the arm 2 and carrying a roll 12.

The roll 12 is maintained in operative engagement, by a spring 13, with a reciprocatory cam slide 14 mounted in the arm 2 and the adjacent portion of the frame 1. A lever 15 operatively connected with the link 9 and pivoted at 16 on said frame is arranged to impart a positive movement to said slide 14 in one direction to raise the anvil 4 and to yieldingly move said slide in the opposite direction by means of a spring 17 interposed between said lever and said slide.

For a more complete description and operation of the parts herein referred to reference may be had to the Patent No. 1,276,652 105 above cited.

Mounted upon the frame 1 above the arm 2 is a hopper 18 constructed and operated similarly to the hopper disclosed in said patent, said hopper being adapted to separate rivet caps from a mass contained therein and to start them down a suitable raceway which delivers them to the setting instrumentalities of the machine.

The present invention pertains particularly to the instrumentalities for transferring the rivet caps from said hopper to said setting instrumentalities and consists of a raceway 19 formed in two parts 20 and 21.

15 The part 20, which is inclined, has oppositely disposed grooves 22 and 23 formed longitudinally thereof for receiving opposite edges of the caps. The upper end of said raceway is attached to the hopper 18 with the grooves 22 and 23 disposed so as to receive the caps from the hopper flatwise, but intermediate of its ends said raceway is twisted so that the caps passing down the same will be turned from flatwise positions 20 to positions on edge whereby said caps will roll rather than slide along said raceway. At the lower end of the inclined portion 20 of said raceway is a substantially straight section 24. This section consists of two parallel plates 25 and 26 arranged one above the other and provided with oppositely disposed grooves 27 and 28, forming continuations of the grooves 22 and 23, said grooves being arranged to receive the edges of the caps, as shown at 29, 29, Figs. 1 and 3, and maintain said caps in substantially vertical positions.

25 The lower strip 26 of said straight raceway section is rigidly secured to the upper surface of the arm 2 and the upper section 25 thereof is pivotally mounted relatively to said section 26 so that the same may be swung upwardly and permit access to the caps 29 in the portion of the raceway formed by said sections.

In carrying out this feature of the invention the plate 25 is provided with ears 30 to receive a hinge pin 31 which is supported in ears 32 formed upon a plate 33 rigidly 30 secured to the upper face of the arm 2 in abutting relation to the plate 26. A spring 34 is secured to the arm 2 by a screw 35 and projects over the plate 25 in yielding engagement therewith to maintain said plate in its operative position relatively to the plate 26.

The inclined raceway 20 not only inclines downwardly toward the arm 2 at an angle

abutting portions of the plates 26 and 33 and adjacent to the terminals of the grooves 27 and 28 in said plates 25 and 26.

The pocket 35 is constructed to hold a cap either in a vertical or flatwise position and 70 is for the purpose of permitting a cap to be turned from a vertical to a flatwise or horizontal position when the same arrives at the lower end of the inclined raceway.

Leading from the pocket 35 toward the 75 lower end 36 of the inclined part of said raceway are grooves 37 and 38 constructed and arranged to guide said caps flatwise. The lower end 36 of said raceway abuts against the end of the horizontal portion 21 80 of said raceway which preferably embodies in its construction two parallelly disposed plates 39 and 40 arranged in spaced relation to provide a slot 41 therebetween.

The inner opposed edges of the plates 39 85 and 40 are grooved at 42 and 43 to coincide with and form continuations of the grooves 37 and 38 for the edges of the caps. The horizontal raceway section terminates in pivoted fingers 44 and 45 pivotally secured 90 by screws 46 to the upper face of said arm 2. The fingers 44 and 45 are also arranged in spaced relation similar to the plates 39 and 40 and the inner opposed edges of said fingers are grooved at 47 and 47', respectively, to form continuations of the grooves 42 and 43, said grooves 47 and 47' terminating in segmental circular shaped recesses 48 and 49 adapted to position the caps, which are advanced along the grooves formed in 100 said horizontal raceway, centrally above the anvil 4 preparatory to the setting of a rivet therein.

105 Springs 50 and 51 are secured to opposite sides of said arm 2 and yieldingly engage the outer edges of the fingers 44 and 45 to maintain said fingers in their normal positions, that is, with the inner edges thereof parallel, said springs permitting said fingers to separate and release said cap when the 110 anvil is moved upwardly into engagement with said cap.

The cam slide 14 has a rectangular extension 52 constructed and arranged to slide along a groove 53 formed in the upper face 115 of the arm 2, and along the space 41 between the plates 39 and 40 and also between the flanges 44 and 45, the edges of said plates and said fingers constituting guides for said extension. The lower abutting portions of 120 the plates 26 and 33 are slotted at 54 and 55 to enable said extension to pass through the pocket 35.

- accomplish this result the forward end 56 of said extension normally moves from a point slightly to the rear of the pocket 35 to a point near enough the anvil 4 to insert 5 a cap in the pocket thereabove. When said extension 52 is in its advanced or partially advanced position it will extend through the pocket 35 and serve as a cutoff for the caps in the inclined raceway 20.
- 10 At this time the lowermost cap, as shown at 57, Figs. 3 and 4, in the inclined raceway section, will, owing to the relation of said raceway to said extension, rest in an inclined position against the side of said ex- 15 tension which is high enough to prevent said cap from falling over flat on its face, but upon the retraction of said extension to a point where the end 56 thereof is at the rear of the pocket 35, said lowermost cap 57 will naturally fall to a horizontal or flatwise position in said pocket 35, as indicated in Figs. 5 and 7, directly in front of the end 56 of said slide and with its edges alining with the slots 37 and 38 in the lower 20 ends of the plates 26 and 33. Upon the forward movement of said slide the end 56 will engage the cap 57 and push the same along the grooves of the raceway 21, from the pocket 35 into the pocket formed by the recesses 48 and 49 thus placing said cap 25 in a position to be moved upwardly and out of said recesses by the upward movement of the anvil 4 when the setting instrumentalities are brought into play to set a rivet in the work.
- 30 Immediately upon the ejection of the cap 57 from the pocket 35 by said extension the next cap in the column of caps in the raceway will be forced down by the other caps therein into an inclined position against said extension in readiness to be transferred from the inclined raceway to said horizontal raceway upon the next operation of said slide.
- 35 Having thus specifically described my invention, what I claim and desire by Letters Patent to secure is:
- 40 1. In a machine of the class described, the combination of a raceway formed in two parts, one of said parts being arranged to guide caps flatwise, the other of said parts being constructed and arranged to guide caps on edge, a slide adapted to move said caps along the first-named part of said raceway and means including said slide for transferring said caps one at a time from the positions on edge to their flatwise positions.
- 45 2. In a machine for feeding circular rivet caps and the like, the combination of an inclined raceway adapted to guide rivet caps on edge, a second raceway adapted to guide said rivet caps flatwise and mechanically operated means for delivering said caps, one at a time, from the first-named raceway 50 to said last-named raceway.
3. In a machine of the class described, the combination of a hopper, an inclined raceway constructed and arranged to receive caps from said hopper flatwise and turn said caps on edge to permit the same to roll 70 along said raceway, a substantially horizontal raceway disposed at the lower end of said inclined raceway adapted to guide rivet caps flatwise and mechanically operated means for transferring said caps from said inclined raceway to said horizontal raceway. 75
4. In a machine of the class described, the combination of a hopper, an inclined raceway adapted to receive caps from said hopper flatwise, said raceway having a twist 80 therein adapted to turn said caps from flatwise positions to positions on edge whereby said caps may be permitted to roll along said raceway, a second raceway adjacent to the lower end of said inclined raceway 85 adapted to maintain caps flatwise and mechanically operated means for transferring said caps from their edgewise positions on said inclined raceway to the flatwise positions on said second-named raceway. 90
5. In a machine of the class described the combination of a hopper, rivet and cap setting instrumentalities, a raceway adapted to guide caps flatwise, a slide for feeding caps along said raceway to said rivet cap setting 95 instrumentalities, an inclined raceway adapted to receive caps from said hopper to permit said caps to roll into a position against the side of said slide and means for operating said slide to transfer said caps one 100 at a time from said inclined raceway to the first-mentioned raceway.
6. In a machine of the class described the combination of a raceway, a slide, an inclined raceway constructed and arranged to 105 permit caps to roll therefrom into an inclined position against the side of said slide, means for retracting said slide to allow the cap inclining thereagainst to fall to a flatwise position in front thereof, and means to move said slide to feed said cap along the first-mentioned raceway. 110
7. In a machine of the class described the combination of a raceway adapted to guide caps flatwise, said raceway having a pocket 115 formed therein adapted to receive said caps on edge and allow the same to be moved to a flatwise position therein, an inclined raceway terminating at said pocket adapted to permit caps to roll therefrom into said 120 pocket, and a slide arranged to be reciprocated through said pocket to transfer said caps one at a time from positions on edge to flatwise positions and to move said caps along the first-mentioned raceway. 125
8. In a machine of the class described the combination of rivet setting instrumentalities, a raceway section provided with a pocket and adapted to guide rivet caps flatwise from said pocket to said setting instru- 130

5 mentalities, an inclined raceway terminating at said pocket adapted to permit caps to roll therefrom into said pocket, a slide arranged to extend through said pocket and to main-
10 tain the lowermost cap in said inclined race-
way on edge, and means for moving said slide in one direction to effect the transfer of the lowermost cap in said inclined raceway from a position on edge to a flatwise position in said pocket, said means being ar-
15 ranged to operate said slide in an opposite direction to move the cap in said pocket along the first-mentioned raceway to said setting instrumentalities.

15 9. In a machine of the class described the combination, of a raceway having a pocket

adapted to contain a cap either on edge or flatwise, a slide normally extending through said pocket, adapted to maintain a cap on edge in said pocket, and means adapted to withdraw said slide from said pocket to effect the fall of said cap to a flatwise position, said means also being adapted to move said slide to eject said cap from said pocket.

20 In testimony whereof I have hereunto set 25 my hand in presence of two subscribing witnesses.

ARTHUR R. HAVENER.
